(57) **CLAIM**

The ornamental design for a water purifier, as shown and described.

DESCRIPTION

FIG. 1 illustrates a front view of the water purifier in accordance with a preferred embodiment of the present invention; FIG. 2 illustrates a top view of the water purifier in accordance with a preferred embodiment of the present invention; FIG. 3 illustrates a rear view of the water purifier in accordance with a preferred embodiment of the present invention; FIG. 4 illustrates a right side view of the water purifier showing removable cover in accordance with a preferred embodiment of the present invention;

FIG. 5 illustrates a left side view of the water purifier showing removable cover in accordance with a preferred embodiment of the present invention;
FIG. 6 illustrates a perspective view of the water purifier in accordance with a preferred embodiment of the present invention;
FIG. 7 illustrates a top perspective view of the water purifier in accordance with a preferred embodiment of the present invention;

FIG. 8 illustrates a top view of the water purifier showing pressure sensitive buttons in accordance with an exemplary embodiment of the present invention; and,
FIG. 9 illustrates another top perspective view of the water purifier showing pressure sensitive buttons in accordance with an exemplary embodiment of the present invention.

The broken line showing of pressure sensitive buttons in FIGS. 8 and 9 is included for the purpose of illustrating and forms no part of the claimed design.
